UNITED STATES PATENT OFFICE

HENRY J. BADLE, OF EVANSTON, ILLINOIS, ASSIGNOR TO MONARK BATTERY COMPANY, INC., A CORPORATION OF DELAWARE

GRID PASTING MACHINE

Application filed May 1, 1930. Serial No. 449,069.

The invention relates to machines for applying the paste to storage battery plates or grids, and has among its other objects the provision of a machine of the kind described that is efficient, durable, simple in construction, and has a large capacity.

Particular objects of the invention are to provide improved means for feeding battery grids into and through a machine of the kind described; to provide improved means for packing the paste into the grids, and to provide improved means for giving the pasted grids a finished appearance.

Many other objects and advantages will appear as this description progresses, reference being had to the accompanying drawings, wherein:

Figure 1 is a side elevation of a machine which embodies the invention.

Fig. 2 is a plan elevation of the improved machine.

Fig. 3 is an enlarged section taken on line 3-3 of Fig. 2.

Fig. 4 is an enlarged fragmentary side elevation of the mechanism which feeds the grids to the pasting apparatus.

Fig. 5 is an enlarged fragmentary section taken on the same line as Fig. 3 illustrating certain details of construction.

Fig. 6 is a section taken on line 6-6 of Fig. 1.

Fig. 7 is a fragmentary plan section taken on line 7-7 of Fig. 6.

Fig. 8 is an enlarged fragmentary section taken on the same line as Fig. 3, a portion being shown in elevation.

Fig. 9 is a section taken on line 9-9 of Fig. 8, and

Fig. 10 is a detail section taken on the same line as Fig. 8 but showing certain parts in changed positions.

Referring to the drawings wherein a preferred embodiment of the invention is illustrated, it will be noted that the improved machine comprises a frame 10 having a bed portion 11 supported upon legs 12. Journalled in the frame is a main drive shaft 14 provided with a sprocket wheel 15 which meshes with a sprocket chain 16 threaded over a pinion 17 secured to the shaft of an

electric motor 18 mounted underneath the machine. A pinion 20 fixed to the shaft 14 meshes with a gear 22 fixed to a shaft 23 which is provided with a pinion 24 meshing with a gear 25, the gear 25 being rigidly secured to a shaft 26 journaled in the frame 10.

The gear 22 meshes with a pinion keyed to a shaft 29 which is rotatably journaled in wall or bracket members 30 mounted upon the bed portion 11. A sprocket-wheel 31 fixed to the shaft 26 meshes with a sprocket-chain 32 which drives a sprocket-wheel 33 fixed to a shaft 34 rotatably journaled in the wall or bracket members 30 (see Fig. 2). A gear 35 fixed to the shaft 34 meshes with gears 37 and 38 which are rigidly secured to the shafts 39 and 40, respectively, the shafts 39 and 40 being rotatably journaled in the wall or bracket members 30.

A pulley 42 mounted upon and constrained to rotate with the shaft 26 drives a belt 43 which is trained over rolls 44 and 45 (see Fig. 3). The roll 44 is rotatably journaled in the bed portion 11 and the roll 45 is rotatably journaled in bearing blocks 47 which are slidably journaled in the bed portion 11 and may be brought into adjusted positions to take up slack in the belt 43. Means for adjusting the bearing blocks 47 preferably comprises rods 50 which are screw-threaded through blocks 51 provided on the bed portion 11, the inner ends of the rods 50 being swiveled to the blocks 47.

The roll 44 is driven by the belt 43 and it is employed to drive improved mechanism 85 for feeding the battery grids into the machine. The feeding means preferably comprises disks 53 fixed to the ends of the roll 44 and provided with crank-pins 54 which are connected by links to downwardly extending arms 56 depending from a feeding plate. The feeding plate 57 is slidably journaled in bracket members 58 which are preferably formed integral with the bed portion 11. The plate 57 rests upon rollers 59 journaled in the bracket members 58. Disposed above the plate 57 to hold it in position upon the rollers 59 are rollers 60 journaled in plates 61 secured to the bracket members 58. The plates 61 support a table 63 upon which

battery grids may be stacked so that they may be manually fed into the feeding mechanism of the machine as required.

Mounted in front of the table 63 is a plate

- 65 adapted to support a pile or stack of the grids which are to be pasted (see Fig. 1). The grids are preferably molded in pairs, as best illustrated in Fig. 7, the pairs being broken in two after the pasting operation.
- 10 In the drawings, the grids are identified by reference character 66. The plate 65 is preferably secured to the bracket members 58 by screws 68 and shims are preferably provided between the plate 65 and the bracket members 58 so that the plate may be adjusted vertically with respect to the plate 57. It is readily understood that when a stack of plates rests upon the plate 65 and the machine is in operation, the plate 57 will reciprocate and at each forward stroke will engage the lowermost pair of grids and advance them to the pasting apparatus.

To insure proper placing of the grids upon the plate 65, an inclined guide-plate 70 is preferably secured to the plate 61 and positioned at the forward edge of the table 63. Then as the plates are fed pair by pair from the bottom of the stack, the plate 70 alines each pair in turn with the forward edge of the feeding plate 57 so that it may be engaged thereby when it advances toward the pasting apparatus. When the grids are placed upon the plate 65 they are preferably alined against a vertically disposed plate 72 which has its lower edge spaced from the plate 65 a distance sufficient to allow the grids to be advanced pair by pair to the belt 43 (see Fig. 3).

In the preferred embodiment of the invention, the grids do not rest directly upon the belt 43, as a web 73 of paper is preferably advanced with the belt and rests thereon to support the grids. The web 73 is withdrawn from a roll 74 mounted upon a shaft 45 75 which is rotatably journaled in slots 76 formed in the frame 10. (See Fig. 1).

A crank shaft 77 has its ends journaled in the wall or bracket members 30 and is driven from the shaft 29 by a sprocket chain 78 (Figs. 8 and 9). The upper ends of links 79 are journaled on bearing portions of the crank shaft 77 and intermediate these bearing portions the crank-shaft is formed into a paddle or blade 77a adapted to agitate the material with which the grids are to be pasted. The lower ends of the links 79 are provided with bosses 79a which ride in vertical grooves 79b formed in the wall or bracket members 30. A shaft 79c has its ends journaled in the bosses 79a and is formed into a paddle 79d intermediate its ends, the construction being such that when the crank shaft 79 revolves the paddle 79d is raised and lowered. During its downward strokes, the paddle 79d remains substantially horizontal

as shown in Fig. 8, but during its upward strokes the paddle is tilted in a nearly vertical position, as shown in Fig. 10. Stops 79e and 79f engageable with the links 79 limit the angular distance through which the paddle oscillates. During its downward strokes the paddle tamps paste into the grids passing beneath it and during its upward strokes it assumes a position permitting it to slide through the paste with a minimum of resistance. Obviously, the paddle 79d feeds the paste downward toward the grids.

Rolls 80, 81 and 82 are formed integral with, or are secured to the shafts 29, 34 and 40, respectively, and are disposed above the belt 43 to feed the paste to and pack it in the grids advanced by the belt 43. The roll 80 is preferably provided with a plurality of angle irons 84 secured to its cylindrical surface, the angle irons being diagonally disposed, as best shown in Figs. 2 and 6. This construction insures that a sufficient quantity of paste will be advanced to the grids.

Rolls 81 and 82 are provided with longitudinally extending grooves 86 and 87, respectively, upon their cylindrical surfaces, which grooves are bent at substantially the middle portions thereof, as best shown in Fig. 2. The roll 86 is rotated through the medium of the gear 35 in a clockwise direction (Fig. 3) so that the lower surface thereof travels in a direction opposite to that in which the grids are advanced. The roll 82 is driven through the medium of a gear 38 and is rotated in a counter-clockwise direction so that its lower surface travels in the same direction as the grids. It will be noted that the grooves 86 and 87 of the rolls 81 and 82, respectively, are bent in such manner that the ends of the grooves come in contact with the advancing grids before the central portions thereof.

The rolls 80, 81 and 82 are disposed between the wall or bracket members 30 which cooperate with an end wall 90 to form a hopper 91 which is not provided with a back wall. It will be noted that paddles 77a and 79d are disposed between the rear wall 90 and the roll 80 so that the paddle 79d forces some paste into the grids before they reach the roll 80. Disposed in the rear end of the hopper 91 and posterior of the roll 82 is a roll 93 formed integral with, or rigidly secured to the shaft 29. The roll 93 is preferably formed from metal and is adapted to engage the upper surfaces of the grids as they are advanced by the belt 43 and to cooperate with the belt to pack the paste firmly in the grids and to polish and finish the upper surfaces thereof. The cylindrical surface of the roll 93 is preferably engaged by a scraper 93a mounted upon a cross-bar 93b secured to the wall members 30. This scraper removes superfluous paste from the roll 93 and insures that it will have a relatively polished

surface adapted to impart a finished appearance to the upper surface of the grids.

As the grids pass from beneath the roll 93 they are preferably engaged by a wiper member 94 formed from spring steel, or other suitable material, the wiper member 94 being secured to and positioned between the wall or bracket members 30. The lower surfaces of the grids rest upon the paper web 83 and the rolls 80, 81 and 93 pack the paste through the interstices in the grid with sufficient force so that a finished appearance is imparted to the lower surfaces of the grids.

When the grids are advanced from the plate 65 to the belt 43, they are engaged by a knurled disk 95 which holds them in engagement with the paper web 73 and also assists in advancing them.

Referring to Fig. 7, it will be noted that the manner in which the grids are arranged in pairs provide a central and substantially solid strip 97 between the grids of each pair which is engageable by the disk 95. The disk is mounted upon a shaft 96 rotatably journaled in the wall members 30 and has a pair of sheaves 98 secured to it, the sheaves 98 being provided with grooves in which belts 100 travel. The belts are preferably of triangular cross-section so that they provide flat surfaces parallel to the upper leg of the endless belt 43 and are adapted to engage the lateral marginal portions and the lugs 66a of each pair of grids.

The belts 100 hold the grids firmly in place upon the paper web 73 and the frictional engagement between the belt and the grids causes the grids to drive the belts and thus results in rotation of the disk 95 which is mounted upon the shaft 96. The belts 100 are trained over a pair of sheaves 105, a pair of sheaves 106 and a pair of sheaves 107. The sheaves 105 are mounted upon a shaft 108 rotatably journaled in the wall members 30. The sheaves 106 are mounted upon a shaft 109 rotatably journaled upon the shaft 29.

The upper legs or lengths of the belts 100 are preferably protected and covered by apron members 112 secured to the wall members 30 (see Fig. 6).

To prevent the belt 43 from sagging, rolls 120, 121, 122 and 123 are provided beneath the rolls 80, 81, 82 and 93, respectively, the rolls 120, 121, 122 and 123 being rotatably journaled in bearing blocks 126, 127, 128 and 129, respectively. The bearing blocks are slidably journaled in the frame 10 and may be brought into a plurality of adjusted positions by means comprising belts 130 (Fig. 1). Each roll 120, 121, 122 and 123 may be adjusted individually so that the belt will be brought into the proper position with respect to the rolls disposed above the belt.

The peripheral speeds of the rolls 80, 81 and 82 are preferably approximately twice the speed at which the grids are advanced

by the belt 43. This is to insure that sufficient paste will be driven into the interstices of the grids. The peripheral speed of the roll 93 is preferably much faster than the peripheral speeds of the rolls 80, 81 and 82 and the roller 93 is preferably driven in a clockwise direction (Fig. 3) so that its lowermost surface will travel in a direction opposite to that in which the grids are advanced. Therefore, the roll 93 functions as a buffing roll and will polish and finish the upper surfaces of the grids as they are advanced by the belt 43. The roll 93 is preferably driven at such speed that its functional engagement with the grids causes it to become relatively hot and this assists in drying the upper surfaces of the grids and permits a relatively wet mixture to be employed as the pasting material. The heat generated in the roll 93 also tends to improve the finish of the upper surfaces of the grids.

The operation of the machine is as follows: A stack of grids 66 is placed upon the plate 65 and the grids are advanced in pairs by the plate 57 which is reciprocated through the medium of the links 55 and crank pins 54. The grids are fed between the disk 95 and the roller 44 and are advanced by the disk and belt 43 through the hopper 91 which has previously been filled with pasting materials, the paddle 79d packs paste into the grids as they pass beneath it, the paddle 77a assisting in agitating the paste so that it will flow downward and not tend to set. This work has heretofore been done by an attendant. The roll 80 also feeds the pasting material to the grids and packs it therein. The grids pass to the rolls 81 and 82 and they complete the work of the roll 80 so that roll 93 is utilized to impart a finished appearance to the upper surfaces of the grids. It will be noted that the cylindrical surface of the roll 93 is smooth so that when the grids pass therefrom there will not be any ridges of pasting material thereon. The chief function of the wiper 94 is to flatten the grids as the roller 93 tends to bend them. When the grids pass from beneath the wiper 94 they are removed by the operator and the paper web is permitted to accumulate upon the floor of the room until it is necessary to dispose of it. The hopper is charged by introducing the paste at the left (Fig. 3) or front end thereof adjacent the wall 90.

No unnecessary limitation is to be understood from the foregoing detailed description, it being the intent to claim the invention as broadly as is permissible, in view of the prior art.

What I regard as new, and desire to secure by Letters Patent, is:

1. In a grid pasting machine, a frame, a hopper for holding paste mounted on the frame, means for advancing grids through the hopper, a plurality of driven rolls in said hopper for packing paste into said grids, said

- rolls being driven in opposite directions, and a roll mounted in said hopper and driven at a higher speed than the first mentioned rolls to polish the pasted grids.
- 5 2. In a grid pasting machine, a frame, a hopper for paste mounted on said frame, said hopper being entirely open at its back end, and a plurality of rolls in said hopper, two of said rolls being driven in opposite directions and being adapted to pack paste into said grids and a third roll being adapted to polish the pasted grids.
- 10 3. In a grid pasting machine, a frame, an endless belt, a web advanced and supported by the belt, a hopper, a plurality of rolls mounted in said hopper, said rolls rotating in opposite directions and disposed so as to nearly contact each other, a polishing roll disposed above said belt posterior of the first mentioned rolls, means for driving said belt and all of said rolls, and means for feeding grids onto said web to pass through said hopper and between said web and said rolls.
- 15 4. In a grid pasting machine, a frame, an endless belt, a web advanced and supported by the belt, a hopper, a plurality of rolls mounted in said hopper for packing paste into said grids, means for driving said rolls in opposite directions, polishing means disposed in said hopper, means for driving said belt and said rolls, and means for feeding grids onto said web to pass through said hopper.
- 20 5. In a grid pasting machine, a frame, an endless belt, a web advanced and supported by the belt, a hopper open at its back end, means for feeding grids onto said web, a plurality of rolls in said hopper for packing paste into said grids, and means for driving said belt and said rolls, said rolls being driven in opposite directions.
- 25 6. In a grid pasting machine, a frame, an endless belt, a plurality of adjustably mounted rolls disposed beneath the belt, a hopper disposed above said rolls and the belt, a plurality of rolls mounted in said hopper and alined with the first-mentioned rolls, and means for driving said belt and said rolls in said hopper.
- 30 7. In a grid pasting machine, a frame, an endless belt, a plurality of endless belts disposed above the first mentioned belt, said plurality of belts engaging only the marginal portions of said grids, means for feeding grids to between the first mentioned belt and said plurality of belts, a hopper through which the grids are advanced by said belts, and means mounted in said hopper for packing paste into said grids.
- 35 8. In a grid pasting machine, a frame, an endless belt, means for feeding grids onto said belt, means for driving said belt, a hopper disposed above said belt, a plurality of rolls in said hopper for packing paste into said grids, a plurality of angle irons fixed to the outer surface of one of said rolls, another of said rolls being provided with grooves extending approximately longitudinally thereof, and means for driving said rolls in opposite directions.
- 40 9. In a grid pasting machine, a driven endless belt for advancing grids, means for feeding grids to said belt in pairs, the grids of each pair being disposed laterally of each other to have two marginal portions thereof lie adjacent each other, means engaging an outer marginal portion of one of each pair of grids, and a rotatable disk engaging said adjacent marginal portions when the grids are fed onto the belt.
- 45 10. In a machine of the character described, means for advancing grids, means for forcing paste into the grids while they are being advanced, and a metallic roll driven at a high speed to finish the grids, said roll being driven at such a speed that frictional engagement between the roll and grids causes the roll to become relatively hot so that the paste is partly dried thereby.
- 50 11. In a grid pasting machine, a frame, a hopper for paste mounted on said frame, said hopper being entirely open at its back end, a plurality of driven rolls mounted in said hopper for packing paste into said grids, and means at the open end of said hopper for polishing the pasted grids.
- 55 12. In a grid pasting machine, a frame, an endless belt for advancing grids, a plurality of adjustably mounted rolls disposed beneath the belt, a hopper disposed above said rolls and said belt, a plurality of endless belts disposed above the first mentioned belt and adapted to engage the marginal portions of said grids, a plurality of rolls mounted in said hopper and alined with the first mentioned rolls, and means for driving said belt and said rolls in said hopper.
- 60 13. In a grid pasting machine, a frame, an endless belt for advancing grids, a plurality of adjustably mounted rolls disposed beneath said belt, a hopper disposed above said rolls and said belt, a plurality of belts disposed above the first mentioned belt and adapted to engage along the marginal portions of said grids, a plurality of rolls mounted in said hopper and alined with the first mentioned rolls, said rolls in said hopper being driven in opposite directions and being adapted to paste said grids, and means for driving said belt.
- 65 14. In a grid pasting machine, a frame, a hopper for paste mounted thereon, said hopper being entirely open at its back end, at least one driven roll mounted in said hopper for packing paste into said grids, and a polishing roll mounted in the open end of said hopper for polishing the pasted grids.
- 70 15. In a grid pasting machine, a frame, a hopper therefor, said hopper being entirely open at its back end, an endless belt, a web

advanced and supported by the belt, at least one packing roll mounted in said hopper, and means at the open end of said hopper for polishing the pasted grids.

5 In testimony whereof, I hereunto affix my signature, this 11th day of April, 1930.

HENRY J. RADLE.
